UNITED STATES PATENT OFFICE.

LONGLEY LEWIS SAGENDORPH, OF PHILADELPHIA, PENNSYLVANIA, AS-SIGNOR OF ONE-HALF TO CHARLES N. HARDER, OF PHILMONT, NEW YORK.

DESIGN FOR A CEILING-PLATE.

SPECIFICATION forming part of Design No. 22,874, dated November 7, 1893.

Application filed September 8, 1893. Serial No. 485,114. Term of patent 14 years.

To all whom it may concern:

Be it known that I, LONGLEY LEWIS SAGENDORPH, a citizen of the United States, residing in the city and county of Philadelphia, State of Pennsylvania, have invented and produced a new and original Design for Metallic Ceiling-Plates, of which the following is a specification.

In the accompanying drawings:—Figure 1, is a plan view of a metallic ceiling plate embodying my design, and Fig. 2, is a sectional view on dotted line 2, 2, of Fig. 1.

A, represents the panel; α , the molding surrounding said panel.

B, indicates the inner frame or stile, and C 15 represents the molding surrounding said inner stile.

D, represents the outer frame or stile with embossed figures, δ , thereon. The corners of the molding, C, are each provided with a 20 suitable rosette, E.

What I claim is—

The design for a metallic ceiling plate substantially as shown and described.

LONGLEY LEWIS SAGENDORPH.
